UNITED STATES PATENT OFFICE.

SAMUEL V. SHAROOD, OF BROCKTON, MASSACHUSETTS, ASSIGNOR OF ONE-HALF TO LUCIUS R. CHURCHILL, OF BROCKTON, MASSACHUSETTS.

AIR-SEPARATOR AND WATER-SEAL FITTING.

SPECIFICATION forming part of Letters Patent No. 784,185, dated March 7, 1905.

Application filed June 23, 1904. Serial No. 213,879.

To all whom it may concern:

Be it known that I, SAMUEL V. SHAROOD, a citizen of the United States, residing at Brockton, in the State of Massachusetts, have invented certain new and useful Improvements in Air-Separators and Water-Seal Fittings; and I do declare the following to be a full, clear, and exact description of the invention, such as will enable others skilled in the art to which it applies to make and use the same.

My invention relates to improvements in air-separating and water-seal devices adapted for use in connection with a steam-pump to enable the latter to be successfully employed for pumping hot water without the use of a receiver; and it consists in the construction, combination, and arrangement of devices hereinafter described and claimed.

The object of my invention is to provide a novel, cheap, simple, compact, and efficient device for use in connection with a steam-pump employed for pumping hot water adapted to effect a positive water seal of the valves of the pump and for venting the air from the pump, thereby preventing the latter from becoming steam-bound.

My improved device is adapted to be used in connection with a steam-pump for exhausting from heating-coils which may be a part of a heating system, steam-vats, driers, and the like devices and, in fact, for exhausting from any source where the condensation from steam-coils requires to be taken away.

In the accompanying drawings, Figure 1 is a side elevation of a water-seal device and air-separator embodying my improvements, showing the same connected to a steam-pump, the latter and the connections being indicated diagrammatically. Fig. 2 is a sectional view of my improved water-seal device and air-separator.

1 in the drawings represents the water end of a steam-pump, to which is connected one end of the suction-pipe 2, through which the water of condensation from the heating or drying system is conducted to the pump. Also connected with the pump is a delivery-pipe 3.

A separator and water seal A is mounted adjacent to the pump and in the form herein

shown is a two-part structure, the separator ⁵⁰ *per se* comprising a chamber 13, closed at its lower end by a head 14 and at its upper end by a head 15, connected thereto by a coupling 16, having two branches 17 and 18, the former receiving the screw-threaded end of a pipe 19, ⁵⁵ connected to the water end of the pump 1 and serving for the exhaust of water therefrom, said pipe being provided with a controlling-valve 20. Coupled to the inner end of the pipe 19 by an elbow 21 is a pendent pipe 22, ⁶⁰ which extends down into the chamber 13 to near the bottom thereof and is adapted to conduct the water and air discharged from the pump to said chamber 13. The coupling 16 is connected to the head 15 by a screw-threaded ⁶⁵ ring 23, and a similar ring or collar 24 connects the upper end of the head with a valve-casing 25, having an outlet-pipe 26 provided with a controlling-valve 27 and containing a ball-valve 28, controlling the port 29, ⁷⁰ communicating with said pipe. The valve 28 may be held closed to its seat by a screw-threaded stem 30, having an outer operating-handle 31 and an inner cage or yoke 32, which receives the valve and allows it to have normal independent movement while retaining it from dislocation. By screwing down the stem 30 the yoke 32 may, however, be brought into direct engagement with the valve, thus holding it immovable on its seat. ⁷⁵

In the operation of the parts thus far described it will be understood that the water entering the chamber 13 through the pipes 19 and 20 remains in said chamber until it reaches the level of the connection 18, when it discharges in the manner hereinafter described, and that the water normally maintains such level in the separator, while the air bubbles up therethrough and finally exhausts to the atmosphere through the valved port 29 and ⁸⁵ pipe 26.

Disposed alongside the separator is a seal-chamber 33, closed at its upper end by a head or coupling 35, the latter having an inlet or connection 36 connected with the connection ⁹⁰ 18 of the separator by a union-pipe 37. Extending down into the chamber 13 to near the bottom thereof is a pendent pipe 38, which is

screw-threaded at its upper end to engage the coupling or head 35 and to also engage an elbow or coupling 39, connected with the pipe 40, communicating with the pipe 37 through 5 said coupling 39 and extending therefrom to the pipe 2, and provided between the seal and said pipe with a check-valve 42, which will allow water to pass from the seal to the pipe 2, but prevents its return, and a cut-off valve 43, 10 by which the flow of water between the seal and pipe may be entirely cut off.

It will of course be understood that the head 15 and casing 25 form an air and vapor chamber which receives the air and vapor from 15 the separator and exhausts the same to the atmosphere. The pipe 26 instead of discharging into the atmosphere may, however, lead to a suitable storage-tank in which the air and vapor may be stored under pressure for 20 subsequent use.

In the operation of the apparatus the pump is started, and the vacuum created in the suction-pipe 2 causes the water therein to rush into the pump. To maintain and aid this 25 vacuum, the valve 20 in the pipe 19 is partially opened, so that the vapor and air and a portion of the water contained in the pump may pass into the separator 13, the same being discharged through the pipe 22 into the separa- 30 tor chamber or casing 13, the water remaining in the said chamber while the air and vapor exhaust through the pipe 26 to the atmosphere. The separator remains full of water up to the line of the pipe 37, and as the water flows above 35 this level a portion of it passes into the casing 33 of the water seal, the more or less constant supply causing the seal-chamber 33 and pipe 38 to be filled up also to the line of the pipe 37, and when there is a greater supply of water 40 the excess flows through the pipe 40 back to the suction-pipe 2. Thus it will be seen that while the air and vapor will be discharged from the steam through the separator the water will remain in the separator and seal and 45 be supplied therefrom back to the suction-pipe, the seal effectually preventing any of the air from passing to the suction-pipe while forming a trap to cause the water to remain therein and become retarded in its flow from 50 the separator, and to thus seal the valves of the pump, making the pump capable of pumping extremely hot water. Hence exposure of the pump-valves cannot occur, and a single pump may be employed to serve the double 55 purpose of a boiler-feeder and suction-pump to secure the return of the water of condens-

sation, thus obviating the necessity of employing two pumps for these purposes. Also by the provision of the water seal no air can possibly return to the suction-pipe when discharged from the pump, thus relieving the latter of a large part of the labor ordinarily thrown thereon. 60

From the foregoing description, taken in connection with the accompanying drawings, 65 the construction and operation of the invention will be readily understood without requiring a more extended explanation.

Various changes in the form, proportion, and the minor details of construction may be 70 resorted to without departing from the principle or sacrificing any of the advantages of the invention.

Having thus described my invention, what I claim, and desire to secure by Letters Pat- 75 ent, is—

1. The combination with a suction-pipe, of a pump, a connection between the pump and suction-pipe, and a combined air-separator and water seal disposed in such connection and operating to receive water, vapor and air from the pump and discharge the vapor and air to the atmosphere and to retain the water and allow the same to pass back to the suction-pipe, substantially as described. 80

2. The combination with a suction-pipe, of a pump, a connection between the said pump and the suction-pipe, a separator in said connection provided with a sealed inlet and an air and vapor chamber having a valved outlet, 90 and a seal in communication with said separator and having a sealed exhaust in communication with said connection with the suction-pipe, substantially as described.

3. An air-separator and water-seal fitting, 95 for use in connection with a pump for pumping hot water, and comprising a separating-chamber having a seal-pipe discharging and extending downwardly therein, and a valved air-vent, in combination with a seal-chamber 100 having a connection with the separating-chamber at an elevated point, and a seal-pipe connected to and extending downwardly in the seal-chamber, substantially as described.

In testimony whereof I have hereunto set 105 my hand in presence of two subscribing witnesses.

SAMUEL V. SHAROOD.
